CLAIM

The ornamental design for forklift, as shown and described.

DESCRIPTION

FIG. 1 is a perspective view of the forklift;
 FIG. 2 is a front view of the forklift;
 FIG. 3 is a rear view of the forklift;
 FIG. 4 is a left side view of the forklift;
 FIG. 5 is a right side view of the forklift; and,
 FIG. 6 is a top view of the forklift.
 FIG. 1 and FIGS. 3 to 6, indicate interior areas of the forklift's cab within broken lines. The portions of the drawings within the broken lines form no part of the claimed design.
